188,013

MARINE CARGO VESSEL OR SIMILAR ARTICLE

Calvin A. Gongwer and Fredman J. Walcott, Jr., Glendora, Calif., assignors to Aerojet-General Corporation, Azusa, Calif., a corporation of Ohio

Filed Feb. 2, 1959, Ser. No. 54,410

Term of patent 14 years

(Cl. D71—1)

Fig. 1 is a side elevational view of the marine cargo vessel showing our new design;

Fig. 2 is a front elevational view thereof;

Fig. 3 is a rear elevational view of the marine cargo vessel; and,

Fig. 4 is a top plan view thereof.

We claim:

The ornamental design for a marine cargo vessel or similar article, as shown.
